UNITED STATES PATENT OFFICE.

EDWARD P. DONNELLAN, OF BROOKLYN, NEW YORK, ASSIGNOR TO STANDARD-JOHNSON CO., INC., OF BROOKLYN, NEW YORK, A CORPORATION OF NEW YORK.

COUNTING MACHINE.

Application filed January 6, 1922. Serial No. 527,438.

To all whom it may concern:

Be it known that I, EDWARD P. DONNELLAN, a citizen of the United States, residing at Brooklyn, in the county of Kings and State of New York, have invented certain new and useful Improvements in Counting Machines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in counting machines of the general type illustrated and described in prior United States Letters Patent #1,160,830, dated November 16th, 1915, and #1,389,634, dated September 6th, 1921; and this invention refers to a machine for counting substantially flat disc-like objects such as coins, bottle seals, buttons, tokens, metal blanks, etc., in lots of comparatively large predetermined number, and to this end a novel tallying mechanism is provided, which automatically locks when the last object of the lot is tallied and delivered out of the machine.

The invention, therefore, has for its principal object to provide an improved tallying mechanism for counting machines; and the invention has for its further object to provide improvements in the means for feeding objects into operative relation to said tallying mechanism.

Other objects of this invention, not at this time more particularly enumerated, will be clearly understood from the following detailed description of the same.

With the objects of the invention in view, the same consists, primarily, in the novel improved counting machine hereinafter set forth; and, furthermore, this invention consists in the novel arrangements and combinations of the various parts, as well as in the details of the construction thereof, all of which will be hereinafter more fully described in the following specification, and then finally embodied in the claims which are appended thereto.

The invention is clearly illustrated in the accompanying drawings, in which:—

Figure 1 is an end elevation, Figure 2 a

plan view, and Figure 3 a front elevation of the novel improved counting machine, made according to and embodying the principles of this invention.

Figure 4 is a detail plan view of the novel tallying mechanism, with the enclosing casing removed, said view being drawn on an enlarged scale; and Figure 5 is a detail front elevation of said novel tallying mechanism, the enclosing casing being in part broken away, said view being also drawn on an enlarged scale.

Figure 6 is a detail vertical section, taken on line 6—6 in said Figure 3, said view being drawn on an enlarged scale.

Similar characters of reference are employed in all of the hereinabove described views, to indicate corresponding parts.

Referring now to said drawings, the reference character 1 indicates the bed-plate 75 of the machine, the same having a vertically disposed central bearing 2 in which is journaled a vertical spindle 3 to the upper end of which is fixed a rotatable table 4, the upper surface of which is 80 preferably flush with the upper surface of said bed-plate. Secured upon the lower end of said spindle 3 is a bevel gear 5. Projecting from the under side of said bed-plate, at suitable locations, are a pair of aligned 85 bearings 6 in which is journaled a transverse shaft 7. Secured upon the inner end of said shaft 7 is a bevel gear 8 which meshes operatively with said bevel gear of said spindle 3. Secured upon the outer end 90 of said transverse shaft 7 is a hand-wheel 9, the same being provided with a suitable handle-member 10 for rotating the same and said shaft 7 whereby through the interconnecting transmission elements the table 95 4 is revolved. Connected with said shaft 7 is a grooved pulley 11 for driving a belt 12, the purpose of which will be subsequently described.

Mounted upon said bed-plate 1, so as to be 100 registered above said table 4, is an article guiding and controlling means, comprising an annular vertical wall portion 13, from the lower end or bottom of which extends an outwardly projecting horizontal flange 105 portion 14. Said annular wall portion 13 incloses an article receiving space or chamber 15 in which the articles to be counted are deposited, said space or chamber being open at the top, and said rotatable table 110

2
 forming the bottom of the same. Said flange portion 14 is undercut at its bottom side to provide an annular space or article runway 16 intermediate said flange portion 5 and the surface of said rotatable table 4, said runway 16 being bounded at its outer margin by a stop-shoulder 17, but being open at its inner margin toward and in communication with the interior of said chamber 15. Said stop-shoulder 17 provides a circular guide or stop whereby articles entering said runway 16 are guided to a place of discharge as the same are carried around by the rotation of the table 4. A portion of 10 said stop shoulder 17 is cutaway at one point, toward the front of the machine, to provide a discharge opening or passage 18 through which the articles leave said runway 16 to be propelled into actuating engagement with a tallying mechanism. When the machine is adapted to count or tally articles such as bottle caps or seals (which are usually comprised of a metallic body having an inner lining of cork or the like), it is advisable to mount said flange-portion 14 relative to the table 4 and bed-plate 1, so that a slight escape-space 19 is provided for intermediate the bottom of 20 said stop-shoulder 17 and the plane of said table and bed-plate surface. This escape-space 19 is of less height than the thickness of the article to be counted, so that notwithstanding the provision of said space the article will engage and be operatively guided by said stop-shoulder 17. The said escape space 19, however, is sufficiently large to permit loose pieces of cork lining or other particles of dirt or foreign material to be flung outwardly therethrough by the centrifugal action produced by the rotating 30 table 4, and by such means the machine is kept clean, and danger of such pieces of cork, dirt or foreign material clogging up the runway 16, or finding access to and interfering with the proper action of the tallying mechanism is eliminated. The means for fastening the article guiding and controlling means thus constructed in the described spaced relation to the table 4 and 40 bed-plate 1, comprises a plurality of threaded posts 20 provided with spacing bosses or shoulders 21, which are fixed to said base-plate 1. That part of the flange-portion 14 lying outward from the stop-shoulder 17 is provided with perforations or other suitably formed openings through which said posts 20 may extend, and thumb-nuts 22 are screwed upon said posts 20 to fasten the article guiding and controlling 50 means in proper assembled position. When the guiding and controlling means is secured to the base-plate 1 as above described, the spacing bosses or shoulders 21 so determine the elevation of the flange-portion 14 that 55 the height of the runway 16 is just sufficient

to admit edgewise beneath the flange-portion 14 and against stop-shoulder 17 the articles to be counted, without permitting the said articles to pile upon one another or overlap each other within said runway. The articles thus admitted into said runway form a continuous train which is moved around the runway by the rotation of the table 4, so that the articles are successively carried to the discharge opening or passage leading 75 out of said runway.

Fixed on said bed-plate 1 is a bearing frame comprising a base-portion 23 and a pair of bearing posts 24. Journaled in said bearing posts 24 is a countershaft 25, upon the outer end of which is fixed a grooved pulley wheel 26 over which runs the heretofore described belt 12 which is operated from the main shaft 7 by the pulley 11, thus driving said counter-shaft 25. Fixed on the inner end of said counter-shaft 25 is a grooved propeller wheel 27. Pivoted on said counter-shaft 25, adjacent to said propeller wheel 27 is a bracket arm 28, having at its free end an axle stud 29 upon which is journaled a grooved idler wheel 30 of comparatively small diameter. Running over said propeller wheel 27 and said idler wheel 30 is a propeller belt 31 which is preferably made of soft rubber or some similar material having a desirable degree of resiliency. A rotation of said propeller wheel 27 throws downwardly said bracket arm to carry the inner end of said propeller belt 31 downwardly so that it crosses transversely the 100 runway 16 opposite the discharge opening or passage 18, whereby the articles as they pass around through the runway are moved into direct engagement with the inner end of the running propeller belt 31, so as to be gripped thereby and forcibly carried outwardly thereby through the said discharge opening or passage 18. This arrangement provides for a positive forcible and rapid successive removal of the articles from the 110 runway, and a positive successive propulsion of the same into actuating contact with the tallying mechanism, as will presently more particularly appear.

Said counter-shaft 25 is so mounted in 115 its bearings as to possess a tension governed vertical movement in said bearings so that the said propeller wheel 25 and its propeller belt 31 may readily and easily accommodate its operation, without undue strain or pressure to any variations in the thickness of the articles operated upon. To this end said bearings are constructed to permit a vertical play of the counter-shaft 25, and the caps of said bearings are provided with 120 spring pressed plungers 32, which exert a downward tensional thrust on said counter-shaft, thus permitting the latter, and the propeller devices thereof, to rise against the tension of said yieldable plungers. 125

The novel tallying mechanism is mounted on said bed-plate 1 in operative relation to the propelling devices above described. The novel tallying mechanism is adapted for the 5 counting of articles in lots of comparatively large numbers. To illustrate the type of tallying device adapted to so count articles in lots of comparatively large number, the drawings show the mechanism designed to 10 count out articles in lots containing either one hundred or two hundred gross, although it will be understood that lots totaling other numerical values may be counted, by modifying the ratio between the parts of the 15 counting wheels or gears according to the grand total desired. The novel tallying mechanism comprises a star wheel or counter-disc 33 provided in its periphery with a series of marginal depressions 34 adapted 20 to be engaged by the perimeters of the articles propelled into actuating contact therewith by the operation of the propeller devices. The said star wheel 33 is fixed upon a vertical spindle 35 which is journaled in 25 the bed-plate 1, and so positioned that said star wheel lies flat upon the surface of said bed-plate. Mounted on said spindle 35 is a ratchet or stop-wheel 36, which is engaged by the free end of a pivoted spring-pressed 30 pawl 37, whereby backward rotation of said star-wheel 33 and the spindle thereof is prevented. Also fixed on said spindle is a spur gear 38. Mounted on said bed-plate on a 35 vertical journal stud 39, so as to rotate in a horizontal plane, is a secondary counter disc or gear 40 which meshes with said spur gear 38. Fixed on said secondary counter disc or gear 40 is a carry-over or transfer dog 41. Journaled in said bed-plate is a 40 vertical spindle 42, upon which is fixed a horizontal primary transfer disc 43 having a plurality of peripheral teeth 44 engageable by said carry-over or transfer dog 41 of said secondary counter disc or gear 40. Fixed 45 on said transfer disc 43 is a carry-over or transfer dog 45. Also fixed on said spindle 42 beneath said transfer disc 43 is a ratchet or stop-wheel 46 having teeth corresponding in number to the number of said teeth 44 50 of the transfer disc 43. Mounted on said base-plate is pivoted spring-pressed pawl 47 which cooperates with said ratchet or stop-wheel 46 to prevent backward rotation of said spindle 42 and said transfer disc 43 55 fixed thereon. For purposes of attaining compactness of construction as to the tallying mechanism, the bed-plate 1 is provided at its forward edge, with a depending vertical flange or bracket plate 48. Journaled 60 in said flange or bracket plate 48 is an outwardly extending spindle 49 upon which is fixed a vertically disposed tally disc 50 having a plurality of peripheral teeth 51 engageable by said carry-over or transfer dog 45 of said transfer disc 43. Mounted on

said flange or bracket-plate 48 is a spring-pressed pivoted pawl 52 which engages the teeth 51 of said tally-disc to prevent backward rotation of the same. Associated with the face of said tally disc 50, is a stop-latch 70 device comprising a hub-portion 53 pivoted on said spindle 49, and from which extend, in diametrically opposite directions, a long or complete revolution stop-latch 54 and a short or half revolution stop-latch 55. Fixed 75 upon the face of said tally-disc 50 in a suitable position is an abutment 56, the same having a socket 57 in which is seated a compression spring 58 which bears or thrusts against one of said stop-latches (as 54), to hold the stop-latch device in normal initial 80 position relative to a stop-projection 59 also fixed on said tally-disc 50, and whereby the stop-latch device is held in normal limited outwardly spaced relation to said abutment 56.

The reference character 60 indicates a casing or cover member which is secured over said tallying mechanism to enclose the same. Said casing or cover-member 60 possesses at its front portion a depending apron 61 which over-hangs and covers the tally-disc 50 and associated mechanism. Fixed on said apron in a proper location is a frame piece 62 having a lateral guideway 63 in 95 which is slidably mounted a barrel or stop-carrier 64. Arranged in said stop-carrier is a stop post 65, having a shank 66 (see Fig. 12) of reduced diameter which projects outwardly from the end of said barrel or stop-carrier 64. Threaded on said shank 66 is a pull-knob 67. Arranged around said shank 66 between said stop-post and the outer end of said barrel or stop-carrier 64 is a compression spring 68, which normally 100 thrusts said stop-post outwardly from the inner end of said barrel or stop-carrier 64. Said apron is provided with a pair of stop-post positioning openings 69 and 70 (see Figs. 3 and 5) through which the free end 110 of said stop-post may be selectively passed to position the same in the path of movement of either the stop-latch 54 or the stop-latch 55 as may be desired.

The spindles 35, 42 and 49 each project 115 outwardly through the casing or cover-member walls, and are respectively provided on their outer free ends with the respective finger-pieces or knobs 71, 72 and 73, whereby the spindles may be respectively turned by 120 hand to set the several counting elements mounted thereon in a normal initial position.

Mounted on said casing or cover-member 125 60, adjacent to said spindle 35, is a counter or total adder mechanism 74, the shaft 75 of which is provided with a bevel gear 76 which meshes with a driving bevel gear 77 fixed on said spindle 35, so that as the spindle 35 turns under the impulse of the articles de- 130

4
livered in actuating relation to the star-wheel 33, the counter or total-adder is operated to record and add a unit as each article operatively actuates said star-wheel, 5 thus providing a visible total record of all articles counted by the operation of the machine.

In order to assure that the articles, as 10 propelled by the propeller devices and propeller belt 31 past the star-wheel 33, operatively engage the same, there is provided a backing or thrust plate 78 which is slidably mounted for limited play in an opposed relation to the periphery of said star-wheel 15 operatively engage the latter. To this end said backing or thrust-plate 78 is longitudinally movable in a guideway provided in the base portion 23 of the bearings 24. Said backing or thrust-plate 78 is provided in its body 20 with a longitudinal slot 79 which engages a pin 80 fixed to said base-plate 1. The forward end of said backing or thrust-plate 78 is provided with an upturned flange 81, 25 which is engaged by a thrust spring 82 backed by the base-portion 23, so that said backing or thrust-plate 78 is mounted for slight rearward yielding, so as to readily accommodate the same to slight variation 30 in the diameter of the articles being counted, and so as to thereby eliminate any danger of jamming of the said articles between the star-wheel and the backing plate, while nevertheless assuring operative passing engagement of the articles with said star-wheel.

In operation the articles are successively gripped by the driving belt 31, and propelled outwardly from the runway 16, and 40 thence forced to pass between the backing or thrust-plate 78 and the star-wheel 33, engaging the seats or depressions 34 of the latter, and thus imparting a rotary impulse to said star-wheel 33 and its spindle 35, 45 thereby rotating the gear 38. In the tallying mechanism illustrated in the drawings, which is adapted to count articles in 200 or 100 gross lots, the spur gear 38 which drives the secondary counter disc or gear 40, possesses a 5 to 1 ratio to said gear 40, so that 50 five revolutions of the star-wheel 33 produces one revolution of the gear 40. Since the star-wheel makes a complete revolution when actuated by the passing of ten articles in 55 operative engagement therewith, it follows that the passing of fifty articles are required to produce five revolutions of the star-wheel 33 and gear 38 whereby one revolution is transmitted to the secondary counter disc or gear 40. The transfer disc 43 possesses 60 sixteen teeth, and at each revolution of said secondary counter disc or gear 40, the transfer or carry-over dog 41 thereof operatively engages a tooth 44 of the transfer disc 43 65 to transmit a partial rotary impulse to the

latter, consequently sixteen revolutions of the secondary counter disc or gear 40 are required to produce one revolution of the transfer disc 43, which means that sixteen times fifty articles have passed in actuating contact with the star-wheel 33, or eight hundred articles. The tally disc 50 possesses thirty-six teeth 51, and at each revolution of said transfer disc 43, the transfer or carry-over dog 45 of the latter operatively engages 70 a tooth 51 of said tally disc to transmit a partial rotary impulse to the latter, consequently thirty-six revolutions of said transfer disc are required to produce one complete revolution of the tally disc, which means 75 that thirty-six times eight hundred articles have passed in actuating contact with the star-wheel 33, or a total of twenty-eight thousand eight hundred, or in other words 80 two hundred gross of articles have been counted. It also follows that a half revolution of the tally disc would mean that 85 eighteen times eight hundred articles have passed in actuating contact with the star-wheel 33, or a total of fourteen thousand four hundred, or in other words one hundred gross of articles have been counted.

When it is desired to count the articles in lots of two-hundreds gross, the stop-post 65 is positioned in the outer opening 69, so 90 that its free end will project toward said tally disc 50 to lie in the path of movement or rotation of the long or complete revolution stop-latch 54, but free from or beyond the path of movement or rotation of the 95 short or half-revolution stop-latch 55. The tally disc is now free to make a complete revolution, and as it approaches the end of a complete revolution, said stop-latch 54 is carried into engagement with the stop-post 100 65, whereby it is forced against the abutment 56, the spring 58 yielding to such movement, so that said abutment is engaged as the last article of the lot to be counted escapes past the star-wheel 33, and consequently further 105 rotation of the tally disc and the associated tallying mechanism is obstructed, and the machine is stopped against further operation until released. The method of releasing the machine for further counting operations, 110 consists in imparting an outward pull to the stop-post 65 which withdraws its free end from engagement with said stop-latch 54, thus permitting the latter to be moved forward by the spring 58 to normal initial 115 position abutting the stop-projection 59. This movement places the end of the stop-latch 54 in front of the end of said stop-post 65, so that as the latter is released, its spring 120 68 projects the same forward against the face of the stop-latch 54. Counting operations may now be resumed, since the stop-latch 54 will be carried by the rotary movement of the tally disc 50 slidingly beneath 125 the end of the stop-post 65 until the latter 130

is passed, whereupon the spring 68 will further project the stop-post 65 inwardly to stand in position to engage the side of the stop-latch 54 as the latter is carried around by a following or successive complete rotation of said tally-disc 50.

If it is desired to count the articles in lots of one hundred gross, the stop-post 65 is pulled outward and the barrel or stop-carrier 64 is shifted sideways or inwardly in the guideway 63 to aline the stop-post 65 with the opening 70. The stop-post 65 being thus positioned, the same is released so that its spring 68 projects the same inwardly to stand in the path of movement of both the stop-latch 55 and 54. At each half revolution of the tally disc 50 the stop-latches 55 and 54 will be successively engaged by the stop-post to stop the machine after each count of one-hundred gross is completed. To resume counting after each one hundred gross is obtained, the stop-post 65 is retracted to allow either one or the other of said stop-latches to shift forward beneath the stop-post in the manner clearly to be understood from the similar operations already above described.

Of course it will be understood that the tallying mechanism may be modified by suitably changing the ratio of its cooperating parts, so that the same may be adapted to count in lots of comparatively large numbers, such as, e. g., lots of one, five or ten thousand, etc.; the automatic stop or interruption of the operations upon the completion of the count of each lot being effected in the same manner as above described.

I am aware that some changes may be made in the general arrangements and combinations of the various devices and parts, as well as in the details of the construction thereof, without departing from the scope of the present invention as set forth in the foregoing specification, and as defined in the appended claims. Hence, I do not limit my invention to the exact arrangements and combinations of the devices and parts as described in said specification, nor do I confine myself to the exact details of the construction of the said devices and parts as illustrated in accompanying drawings.

I claim:—

1. In a counting machine, the combination with a rotatable star-wheel device, of means for successively delivering and propelling articles to be counted in actuating engagement with said star-wheel device, a rotatable tally-disc, accumulative transfer means actuated by said star-wheel device to rotate said tally-disc, an axially pivoted stop-latch device having oppositely extending stop-latches, one of said stop-latches being longer than the other, a retractable spring projected stop means, an adjustable means supporting said stop-means to selec-

tively position the same for projection into the path of movement of said longer stop-latch or into the path of movement of both of said stop-latches, an abutment on said tally-disc for determining the stopping position of said stop-latch device, spring means for normally holding said stop-latch device in slightly advanced position relative to said abutment, and means on said tally-disc for determining said advanced position of said stop-latch device.

2. In a counting machine, the combination with a rotatable spindle provided with a star-wheel, of means for successively delivering and propelling articles to be counted into actuating engagement with said star-wheel, a rotary counter means in geared relation to said star-wheel spindle, a carry-over dog fixed on said rotary counter means, a rotary toothed transfer disc, the teeth of said transfer disc being operatively and successively engaged by said carry-over dog to transmit at the completion of each revolution of said counter means a partial rotary movement to said transfer disc, a transfer dog fixed on said transfer disc, a rotary toothed tally disc, the teeth of said tally disc being operatively and successively engaged by said transfer dog to transmit at the completion of each revolution of said transfer disc a partial rotary movement to said tally disc, an axially pivoted stop-latch device having oppositely extending stop-latches, one of said stop-latches being longer than the other, a retractable spring projected stop means, an adjustable means supporting said stop-means to selectively position the same for projection into the path of movement of said longer stop-latch or into the path of movement of both stop-latches, an abutment on said tally-disc for determining the stopping position of said stop-latch, spring means for normally holding said stop-latch device in slightly advanced position relative to said abutment, and means on said tally-disc for determining said advanced position of said stop-latch device.

3. In a counting machine, the combination with a bed-plate of a rotatable feed table, a guide ring having a horizontal flange parallel to and spaced above said table to form a circular article runway arranged over the marginal portions of said table, said guide ring having an outlet passage communicating with said runway, and a rotatable article propelling means having an operative portion thereof disposed in said outlet passage to extend transversely across said runway to successively grip and propel outward the articles moved around said runway to said outlet passage.

4. In a counting machine having a counting mechanism and article feeding and guiding means, an article propelling means

6
intermediate said counting mechanism and article feeding and guiding means, comprising a driven wheel, a bracket arm pivotally arranged relative to the axis of said driven wheel, an idler wheel mounted on the free end of said bracket arm, a propeller belt mounted to run over said driven wheel and said idler wheel, and said propeller belt normally cooperating with said article feeding and guiding means to remove articles there-

from and propel the same into actuating engagement with said counting mechanism.

In testimony, that I claim the invention set forth above I have hereunto set my hand this 25th day of November, 1921.

EDWARD P. DONNELLAN.
